UNITED STATES PATENT OFFICE.

ALBERT E. DOMAN, OF ELBRIDGE, NEW YORK, ASSIGNOR, BY MESNE ASSIGNMENTS, TO DYNETO ELECTRIC CORPORATION, OF SYRACUSE, NEW YORK, A CORPORATION OF NEW YORK.

MOTOR-GENERATOR.

1,247,650.

Specification of Letters Patent. Patented Nov. 27, 1917.

Application filed July 27, 1914. Serial No. 853,428.

To all whom it may concern:

Be it known that I, ALBERT E. DOMAN, a citizen of the United States, and resident of Elbridge, in the county of Onondaga, in the

5 State of New York, have invented new and useful Improvements in Motor-Generators, of which the following, taken in connection with the accompanying drawings, is a full, clear, and exact description.

10 This invention relates to certain improvements in dynamo electric machines of the class shown in my pending application Serial No. 846,756, filed June 23, 1914, except that it relates more particularly to the construction of the casing for inclosing the armature, field windings and commutator.

15 The main object is to reduce the weight and at the same time to increase the strength and durability of the case or housing, without sacrificing its magnetic efficiency.

20 Another object is to reduce the cost of production by making the main shell and its reinforcing shell or tube to exact sizes so that they may be interfitted and the various adjuncts of the complete machine assembled thereon without laborious or expensive milling.

25 Other objects and uses of specific parts of the casing will be brought out in the following description.

In the drawings—

30 Figures 1, 2 and 3 are respectively a side elevation and opposite end views of a dynamo electric machine embodying the various features of my invention.

35 Figs. 4, 5 and 6 are respectively a longitudinal section and transverse sections taken on lines 4—4, 5—5 and 6—6, Fig. 1, omitting the armature, field windings and bearings for said armature.

40 The casing comprises a one-piece sheet-metal shell or tube —1— of magnetizable material, preferably of pressed steel, having a polygonal (in this instance hexagonal) 45 main body —2— and a reduced or relatively smaller cylindrical end —3— coaxial therewith, the outer end of the main body being open to approximately its full interior area except at the angles where the stock is bent inwardly forming flanges —4— to which a cover-plate or head —5— may be secured by

bolts —6— for excluding dust and other foreign matter and also to support the bearing, as —7—, for the adjacent end of the armature shaft —a—.

55 The opposite or smaller end of the case is substantially closed by an integral end wall —8— having a relatively small opening —9— for receiving a bearing plate as —10—, for the adjacent end of said armature shaft, said bearing plate being secured to the end wall to form a dust proof joint therewith.

60 A reinforcing shell or tube —11— of magnetizable sheet metal and preferably of 65 pressed steel is tightly fitted flat-wise within the polygonal portion of the shell —1— and is therefore of substantially the same transverse form and exterior size as the interior of this portion of the shell so as to contact therewith at all points and thereby not only 70 strengthen the shell but also build up its magnetic field to the desired cross section, it being understood of course that the sides of the shell and its reinforcement are substantially flat.

75 The length of this reinforcement is somewhat less than that of the larger portion of the shell in which it is mounted and terminates short of the ends thereof to correspond approximately to the length of the pole pieces, as —12—, which are secured against the inner faces of the flat sides of the reinforcement by screws —13— passing through registering bolt holes in the shell 80 —1— and ring —11— so that the same screws serve to hold the shell, ring and pole pieces in fixed relation.

85 The cylindrical portion of the case is provided with a circumferentially elongated 90 opening —15— in one side thereof to permit access to the commutator and its brushes for adjustment or repairs, said opening being normally closed by sliding cover —16— preferably of light sheet metal fitted on the 95 periphery of the shell to form a dust proof joint but movable to one side of the opening when necessary.

95 By using pressed steel for the main shell and its reinforcement, the weight of the 100 case may be greatly reduced and its strength and durability greatly increased, the rein-

forcing ring serving not only to stiffen the case but also to give it the necessary field for magnet circuits.

What I claim is:—

- 5 A case for dynamo electric machines comprising two coaxial pressed steel tubes, both magnetizable and tightly fitted one within the other so as to contact flatwise at all points about their axes, pole pieces in contact with the inner face of the inner tube, and clamping bolts passed through both
- 10

tubes and engaged with the pole pieces for clamping the inner tube firmly to the outer tube, and holding the pole pieces in operative position.

15

In witness whereof I have hereunto set my hand this 20th day of July, 1914.

ALBERT E. DOMAN.
